[57] CLAIM

The ornamental design for the bicycle storage compartment, as shown.

DESCRIPTION

FIG. 1 is a side perspective view of a bicycle storage compartment showing my new design, the bicycle shown in broken lines is for illustrative purposes only and form no part of the claimed;

FIG. 2 is a top plan view thereof;

FIG. 3 is a side elevational view thereof, the opposite side elevational view being a mirror of that shown;

FIG. 4 is a bottom plan view thereof;

FIG. 5 is an opposite end elevational view thereof;

FIG. 6 is an opposite end elevational view thereof;

FIG. 7 is a side perspective view of a bicycle storage compartment showing a second embodiment of my new design, the bicycle shown in broken lines is for illustrative purposes only and form no part of the claimed design;

FIG. 8 is a top plan view of FIG. 7;

FIG. 9 is a side elevational view of FIG. 7, the opposite side elevational view being a mirror image of that shown;

FIG. 10 is a bottom plan view of FIG. 7;

FIG. 11 is an end elevational view of FIG. 7; and,

FIG. 12 is an opposite end elevational view of FIG. 7.
